UNITED STATES PATENT OFFICE.

GEORGE F. ISGRIG, OF ST. LOUIS, MISSOURI, ASSIGNOR OF ONE-HALF TO JOHN G. SATTERFIELD, OF ST. LOUIS, MISSOURI.

HOT-AIR FURNACE.

Application filed December 10, 1923. Serial No. 679,559.

To all whom it may concern:

Be it known that I, GEORGE F. ISGRIG, a citizen of the United States, residing at St. Louis, Missouri, have invented a new and useful Hot-Air Furnace, of which the following is a specification.

This invention relates to hot air furnaces.

An object of the invention is to provide an improved hot air furnace embodying 10 means for utilizing to the fullest extent the heat of the heated gases and products of combustion passing from the furnace to heat the air confined about the furnace.

Another object of the invention is to provide 15 a hot air furnace having an outlet pipe for the smoke and gas, and means for obtaining a direct draft from the furnace to the pipe or for circulating the smoke and gas through a drum to obtain maximum advantage from the hot smoke and gases to 20 heat the air confined about the furnace.

Other objects will appear from the following description, reference being made to the drawing in which—

25 Fig. 1 is a cross sectional view of the furnace embodying the present invention.

Fig. 2 is a vertical sectional view on the line 2—2 of Fig. 1.

The combustion chamber 1 and the enclosing 30 air drum 2 having pipes 3 for conducting the hot air to points of use are of usual construction.

The present invention consists of devices 35 located between the combustion chamber 1 and the smoke outlet pipe or flue 4 for obtaining a direct draft or for retarding and circulating the hot smoke and gases to obtain maximum advantage therefrom in heating the air in the air chamber.

40 As shown, the combustion chamber 1 supports at its upper end a drum comprising a lower wall 5, a side wall 6 spaced from the wall of the drum 2 and an upper wall 7 closing the upper end of the drum and opening 45 into the outlet pipe or flue 4. The diameter of said drum is considerably greater than the diameter of the combustion chamber 1 and the opening from the combustion chamber into said drum is the full diameter 50 of the top of the combustion chamber.

A baffle wall 8 rests upon a number of supports 9 which extend upwardly from the bottom wall 5 of the drum. The baffle wall 8 is of less diameter than the drum leaving a

space 10 between the drum wall 6 and the 55 edge of said baffle wall for the passage of the smoke and heated gases when the direct communication from the combustion chamber 1 to the outlet pipe or flue 4 is closed. A hole 11 through the center of the baffle 60 wall 8 is fully as large as the opening to the outlet pipe or flue 4 and is in axial alignment therewith. The hole 11 is equipped with a sliding damper or closure 12 supported on flanges 13 and connected with an 65 operating rod 14 extending outwardly through the drum wall 6 and through the air drum 2. By means of the rod 14 the damper or closure 12 can be moved from closed to open position and vice 70 versa. When it is desired to have direct draft the closure or damper 12 is opened. After the fire is well started and it is desired to increase the heat, the closure or damper 12 is closed thereby diverting the hot 75 smoke and gases through the space 12 between the drum 6 and the edge of the baffle 8.

A spiral 15 beginning at the point 16 at the edge of the hole 12 and running about 80 three-fourths, more or less, around the space 12 and around the opening into the pipe or flue 4, has a continuing circular portion 17 forming about three-fourths of a circle within and slightly spaced from the drum wall 6. 85 This leaves an open space 18 through which the hot smoke and gases may pass to the inside of the circular wall portion 17 and thence follow the spiral wall 15 to the opening into the pipe or flue 4. In this way the 90 heated smoke and gases are circulated so as to radiate the heat therefrom to the air confined in the air drum 2 about the furnace.

From the foregoing it will be seen that my 95 invention is a simple and efficient one and obtains all of its intended objects and purposes. The structure may be easily manufactured and assembled and the use thereof is highly advantageous as it obtains more 100 heat from less fuel than in the case of furnaces having only direct communication from the combustion chamber to the outlet pipe or flue.

I am aware that the construction and arrangement may be varied in numerous particulars without departure from the nature and principle of the invention, and I do not restrict myself unessentially,

What I claim and desire to secure by Letters Patent is:—

1. In a hot air furnace, the combination with a combustion chamber and a smoke outlet flue, of a drum opening into the combustion chamber and into the outlet flue, a baffle wall in the drum of greater diameter than the opening into the combustion chamber spaced from the bottom of the drum and from the side wall of the drum, and a spiral wall upon the baffle forming a tortuous passage from the edge of the baffle wall to the opening into the outlet flue.
2. In a hot air furnace, the combination with a combustion chamber and a smoke outlet flue, of a drum opening into the combustion chamber and into the outlet flue, a baffle wall in the drum of greater diameter than the opening into the combustion chamber spaced from the bottom of the drum and from the side wall of the drum, a spiral wall upon the baffle forming a tortuous passage from the edge of the baffle wall to the opening into the outlet flue, and means for providing direct communication from the combustion chamber to the outlet flue.
3. In a hot air furnace, the combination

with a combustion chamber, an outlet flue and an air drum, of a drum at the top of the combustion chamber opening into the combustion chamber and into the outlet flue, a baffle wall supported in said drum of greater diameter than the opening into the combustion chamber and spaced from the bottom and side walls of said second drum, and a tortuous passage from the edge of said baffle wall to the opening into said outlet flue.

4. In a hot air furnace, the combination with a combustion chamber, an outlet flue and an air drum, of a drum at the top of the combustion chamber opening into the combustion chamber and into the outlet flue, a baffle wall supported in said drum of greater diameter than the opening into the combustion chamber and spaced from the bottom and side walls of said second drum, a tortuous passage from the edge of said baffle wall to the opening into said outlet flue, a direct passage through said baffle wall to the opening into said flue, and a device for opening and closing said passage.

GEORGE F. ISGRIG.
